STOCKING

Filed June 21, 1927

Inventor

Patrick P. La Montagne

By *Ammons H. Lang* Attorney

UNITED STATES PATENT OFFICE.

PATRICK P. LA MONTAGNE, OF KANKAKEE, ILLINOIS, ASSIGNOR TO POPE MACHINE COMPANY, OF KANKAKEE, ILLINOIS, A CORPORATION OF ILLINOIS.

DESIGN FOR A STOCKING.

Application filed June 21, 1927. Serial No. 22,516. Term of patent 14 years.

To all whom it may concern:

Be it known that I, PATRICK P. LA MONTAGNE, a citizen of the United States, residing in the city of Kankakee, county of Kankakee, State of Illinois, have invented a new, original, and ornamental Design for a Stocking, of which the following is a specification, reference being had to the accompanying drawing, forming a part thereof.

In this drawing:

Figure 1 is a side view of a stocking embodying my new design; and

Figs. 2 and 3 are fragmentary views of the foot and top portions of the stocking illustrated in Fig. 1, considerably magnified, to illustrate the characteristic features, respectively, of these different portions of the article.

The drawing shows a ribbed stocking having the sole, toe, and heel portions of contrasting stitch from that of the ribbed leg and instep portions, the garter-top or cuff being of a different rib-formation; the rib-knitting in the leg and instep portions being characterized by the so-called "four-and-one" type and by longitudinal grouping of the ribs thereof, and the rib-knitting in the garter-top being likewise characterized by the so-called "one-and-one" type.

I claim:

The ornamental design for a stocking, substantially as shown and described.

PATRICK P. LA MONTAGNE.
